BINDER

Daymond J. Akin, Akron, Ohio

Application October 22, 1936, Serial No. 107,033

4 Claims. (Cl. 129—1)

This invention relates to binders.

The general purpose of the present invention is to provide an improved binder for releasably receiving and retaining one or more pamphlets, magazines, etc., as for example pamphlets of note paper, lesson pamphlets, volumes of a magazine or other periodical and the like.

The foregoing and other purposes of the invention are attained in the binder illustrated in the accompanying drawing and described below.

It is to be understood that the invention is not limited to the specific forms thereof shown and described.

Of the accompanying drawing:

Figure 1 is a perspective view of an open binder embodying the invention.

Figure 2 is a section along line 2—2 of Figure 1.

Figure 3 is an enlarged view of the right end of Figure 2, illustrating the manner of using the improved binder.

Figure 4 is a section on line 4—4 of Figure 3.

Figure 5 is a rear corner view of a type of pamphlet or magazine adapted for use in the improved binder, and

Figure 6 is a section on line 6—6 of Figure 5.

Referring to the drawing, the numerals 10, 10 designate pamphlets which may be of that type in which the sheets are bound together by staples 11, 11. To adapt such pamphlets for use with the present binder they are provided at their rear or back edges with pins or projectors 12, 12 having enlarged heads 12^a, 12^a. These may be, as shown, formed integral with the staples 11, 11 or attached thereto, or otherwise attached to the pamphlets 10 to project from the rear edges thereof at spaced points.

The improved binder is shown at 13 and may be of any suitable flexible or stiff sheet material having suitably secured on the inside thereof a channel member 14, in the upper face of which are lateral slots 15, 15 for receiving the pins or projections 12 on the pamphlets, etc. to be bound. At the sides of the channels and at the ends of the slots 15, are openings 16, 16 large enough to permit passage of the enlarged heads 12^a on the pins into the channel member with the heads engaged under the edges of slots 15, the slots 15 being wide enough to permit free passage of the shanks of pins 12, and heads 12^a being larger than the width of the slots so as to be retained in the channel against upward displacement therefrom.

In order to lock, releasably, the pamphlets in the channel against lateral displacement therefrom, locking members 17, 17 are arranged in

the channel inwardly behind openings 16. These members are preferably inwardly curved or sloping as shown, so as to provide spaces 18, 18 into which the heads 12^a of pins 12 may be inserted and whereby the locking members 17 may be depressed out of the way to permit insertion of a pamphlet into the binder, by engaging the pins 12 in openings 16 and in spaces 18 and then pulling the pamphlets laterally whereby heads 12^a of pins 12 depress the locking members 17 as shown in Figure 3 and at the left side of Figure 4.

The cam-shaped locking members 17 may be yieldingly urged upwardly into locking position, as shown best at the right of Figure 4 by being secured to or formed upon a leaf spring member 19 secured to the channel at 20 and having yielding wings 19^a, 19^a supporting the locking members 17.

In order to permit removal of a pamphlet from the binder, the locking members 18 may be arranged to be depressed by extending levers 21, 21 out of the ends of the channel member 14, as shown.

It will be apparent that the binder is so devised that pamphlets may be inserted or removed from either side thereof, the openings 16, locking members 17 and levers 21 being duplicated at both sides of the channel. However, it is obvious that it is within the spirit of the invention to provide openings 16 and locking members 17 and levers 19 at only one side of the channel, the pamphlets being inserted and removed at only one side.

Certain magazines or pamphlets 25 (Figures 5 and 6) are bound by staples 26, in the manner indicated. These may be adapted to the present binder by insertion of pins 27 from the back edge of the magazine or pamphlet between the sheets thereof, the pins being formed of doubled wire or the like with a loop providing an enlarged head 27^a, the pin being inserted between the 40 sheets and through the staples and the ends of the wire may be bent in front of the staples as shown at 27^b, 27^b.

Modifications of the invention may be resorted to without departing from the spirit thereof or 45 the scope of the appended claims.

What is claimed is:

1. In a binder having a channel member secured to the inside thereof with spaced lateral slots in its upper face and enlarged openings in 50 the channel at the ends of said slots for receiving one or more pamphlets having correspondingly spaced pins with enlarged heads projecting from the back-edges thereof, said heads being engageable through said openings whereby the pins may 55

- be laterally engaged in said slots and the pamphlet retained in the binder by engagement of said enlarged heads under said slots, the combination of cam-shaped locking members behind said 5 openings for releasably locking said pins against lateral displacement from the channel, means normally urging said locking members upwardly into locking positions, said members being adapted to be depressed by said pins by inserting said 10 pins through said enlarged openings and laterally urging the pins against the cam-shaped locking members, and means extending out of the ends of the channel member for depressing said locking members at will to permit removal of a pamphlet from the binder.
2. In a binder having a channel member secured to the inside thereof with spaced lateral slots in its upper face and enlarged openings in the channel at the ends of said slots for receiving 20 one or more pamphlets having correspondingly spaced pins with enlarged heads projecting from the back-edges thereof, said heads being engageable through said openings whereby the pins may be laterally engaged in said slots and the pamphlet retained in the binder by engagement of said enlarged heads under said slots, the combination of cam-shaped locking members behind said 25 openings for releasably locking said pins against lateral displacement from the channel, means normally urging said locking members upwardly into locking positions, said members being adapted to be depressed by said pins through said enlarged openings and laterally urging the pins against the cam-shaped locking members.
3. In a binder having a channel member secured to the inside thereof with spaced lateral slots in its upper face and enlarged openings in the channel at the ends of said slots for receiving one or more pamphlets having correspondingly spaced pins with enlarged heads projecting from the back-edges thereof, said heads being engageable through said openings whereby the pins may be laterally engaged in said slots and the pamphlet retained in the binder by engagement of said enlarged heads under said slots, the combination of cam-shaped locking members behind said openings for releasably locking said pins against lateral displacement from the channel, means normally urging said locking members upwardly into locking positions, and means extending out of the ends of the channel member for depressing said locking members at will.
4. In a binder having a channel member secured to the inside thereof with spaced lateral slots in its upper face and enlarged openings in the channel at the ends of said slots for receiving one or more pamphlets having correspondingly spaced pins with enlarged heads projecting from the back-edges thereof, said heads being engageable through said openings whereby the pins may be laterally engaged in said slots and the pamphlet retained in the binder by engagement of said enlarged heads under said slots, the combination of locking members behind said openings for releasably locking said pins against lateral displacement from the channel, means normally urging said locking members upwardly into locking positions, and means extending out of the ends of the channel member for depressing said locking members at will.

DAYMOND J. AKIN.
